UNITED STATES PATENT OFFICE.

EVERETT S. HALL, OF ALANREED, TEXAS.

DEVICE FOR OPENING AND CLOSING GARAGE DOORS.

Application filed October 28, 1926. Serial No. 144,799.

The present invention is directed to improvements in devices for opening and closing garage doors, or the like.

The primary object of the invention is to provide a device of this character constructed to automatically open the doors as an automobile approaches the garage, closing the doors after entering the garage, the construction being such that the doors can be automatically opened and closed when the automobile is being driven from the garage.

Another object of the invention is to provide a door opening and closing mechanism so arranged that when an automobile is occupying the garage the doors cannot be opened from the outside of the garage.

Still another object of the invention is to provide door actuating mechanisms so located that they can be easily encountered by the wheels of the automobile without any undue steering skill.

In the drawings:

Figure 1 is a top plan view of the operating mechanisms.

Figure 2 is a sectional view on the line 2—2 of Figure 1.

Figure 3 is a sectional view on line 3—3 of Figure 1.

Figure 4 is a sectional view on the line 4—4 of Figure 1.

Figure 5 is a sectional view on the line 5—5 of Figure 4.

Figure 6 is a sectional view on the line 6—6 of Figure 5.

Referring to the drawings, the numeral 1 designates the door frame of a garage, to the sides 2 of which are hingedly connected doors 3, each consisting of hingedly connected sections 4 and 5. By sectionalizing the doors 3 it will be obvious that when the doors are opened they will occupy a very little space within the garage. The top sill 6 of the door frame is formed with a longitudinal groove 7 having inwardly inclined branches 8, the lugs 9, carried by the upper edges of the sections 5 being slidably guided in the groove and branches during the opening and closing of the doors. The sections 4 of the doors have secured to their inner faces loops 10, the purpose of which will appear later.

In order to properly mount the door-operating mechanism, a pit 11 is provided and extends under the frame 1, there being pits 12 and 13 associated with the pit 11, the former being located within the garage while the latter is located in the approach to the garage.

The upper ends of the respective pits are provided with cover plates 14 of any suitable material.

In the pits 12 and 13 are located blocks 15 and 16, having mounted thereon bearings 17 and 18, respectively, and journaled in these bearings is a main actuating shaft 19. Fixed to the shaft 19 are pinions 21 and 22 and 23 and 24, the former pair being located in the pit 12 while the latter pair is located in the pit 13, as clearly shown in Figure 1.

Suitably mounted upon the blocks 15 and 16 are guide members 25 and 26, respectively. These guide members are provided with roller bearings 27 and 28, respectively. Vertically slidable in the respective guide members 25 and 26 are rack bars 29 and 29' and 30 and 30', respectively, the rear or smooth sides thereof engaging the rollers 27 and 28 to relieve friction during the vertical movement of the bars and at the same time hold said bars in their proper relationship with respect to the associated pinions. It will be observed that the rack bars 29 and 29', as well as the rack 30 and 30' are arranged in diagonal relation and upon opposite sides of the shaft 19, and since these rack bars mesh with the associated pinions 21 and 22, rotary movement will be imparted to the shaft 19 in reverse direction when the rack bars are alternately depressed.

Owing to the limited space in the garage the rack bars 29 and 29' and associated parts are arranged comparatively close to each other.

Slidably supported longitudinally within the pit 11 are bars 31 and 32, the latter being of greater length than the former, said bars being provided upon their inner ends with rack portions 33 and 34 adapted to mesh with the pinion 35 and from opposite sides thereof, as clearly shown in Figures 3 and 4 of the drawings. It will be apparent that upon rotation of the shaft 19 the parts 31 and 32 will slide in reverse directions, the purpose being obvious. The outer ends of the bars 31 and 32 are provided with rack teeth 36 and 37, respectively, which mesh respectively with the pinions 38 and 39 fixed to the lower ends of the vertically disposed door-operating shafts 40 and 41. These shafts have their upper ends journaled in the top sill 6 of the door frame and their lower ends suitably journaled in the pit 11.

The shafts 40 and 41 have fixed thereto

horizontally disposed arms 42 in which are formed longitudinal slots 43 for slidably engaging the loops 10, as more clearly illustrated in Figure 6 of the drawings. It will be apparent that upon sliding movement being imparted to the bars 31 and 32 rotary movement will be imparted to the door-operating shafts 40 and 41 to open or close the doors.

10 The operation of the device is as follows: The door 3 being closed, as indicated by dotted lines in Figure 1 of the drawings, a car in approaching the garage encounters the rack 30 and depresses the same, thus rotating the shaft 19 clockwise through the medium of the associated pinion 23. This operation causes the bars 31 and 32 to slide outwardly, thus rotating the door operating shafts 40 and 41, whereupon the arms 42 are 15 swung inwardly compelling the sections 4 and 5 of the door to fold inwardly to permit the car to pass freely through the door opening. It will be observed upon reference to Figure 3, that at this point of the operation the rack bar 30' has been elevated, likewise the rack bar 29 within the garage. It is essential that the rack bars 30 and 30' be a sufficient distance apart in order that a front wheel of the car will encounter the 20 rack bar 30 after the rear wheel of the car has passed over the bar 30'. The car, after passing through the door opening, is driven into the garage until one front wheel encounters the now elevated rack bar 29, which 25 being depressed by the weight of the car rotates the shaft 19 in a reverse direction to close the doors. Since the bar 29 is now de-

pressed and the bar 29' is elevated, the driver, upon leaving the garage, drives the front wheel of the car upon the rack bar 29', which being depressed causes the door to 30 automatically open. Upon the depression of the bar 29, the associated bar 29' will be elevated, as well as the bar 30' and since the bar 30' is now elevated a rear wheel of the 35 car, when backing from the garage will encounter the said bar 30' and depress the same to rotate the shaft 19 in a direction to close the doors.

When a car is occupying the garage with 40 one of its wheels upon the rack bar 29, the parts will be held against movement, thus holding the door locked as long as the car holds the bar depressed.

The invention, while primarily designed 45 for use in connection with garage doors, can be used with equal success with closures of other types.

Having thus described the invention, I 50 claim:

A device of the class described, comprising 55 a pair of doors, a shaft, said shaft having paired pinions fixed thereto adjacent its ends and upon opposite sides of the doors, a vertically movable wheel operated rack bar in mesh with the pinion of each pair, the bars of each pair being located upon opposite 60 sides of the shaft and capable of being alternately and successively elevated or lowered 65 to open or close the doors, and operative 70 connections between the shaft and doors.

In testimony whereof I affix my signature.

EVERETT S. HALL. [L.S.]
